[57] CLAIM

The ornamental design for a carrying case for a circular saw blade, as shown and described.

DESCRIPTION

FIG. 1 is a perspective view of a carrying case for a circular saw blade showing my new design;

FIG. 2 is a right side elevational view thereof;

FIG. 3 is a rear elevational view thereof;

FIG. 4 is a bottom plan view thereof; and

FIG. 5 is a cross-sectional view taken along line 5—5 of FIG. 1.
